White, Frost & Evans
his ATTORNEYS

UNITED STATES PATENT OFFICE.

ALFRED R. KOLB, OF SAN FRANCISCO, CALIFORNIA.

APPARATUS FOR PURIFYING GASES.

Application filed November 10, 1920. Serial No. 423,140.

To all whom it may concern:

Be it known that I, ALFRED R. KOLB, a citizen of the United States, and a resident of the city and county of San Francisco and 5 State of California, have invented a new and useful Apparatus for Purifying Gases, of which the following is a specification.

My invention relates to the preheating and purifying of gases with special reference to the manufacture of sulfuric acid.

An object of the invention is to provide an improved means and method of preheating the sulfur gases and the elimination by oxidation of sublimed sulfur entrained in 15 the gases. Further objects include the provision of means and method characterized by great economy in fuel, accurate temperature control and simplicity and cheapness of the equipment.

20 Other objects of the invention together with the foregoing will be set forth in the following description of the preferred process and the preferred embodiment of means for practicing the same, which is illustrated 25 in the drawings accompanying and forming part of the specification. It is to be understood that I do not limit myself to the showing made by the said description and drawings, as I may adopt variations of my 30 preferred forms within the scope of my invention as set forth in the claims.

In the drawings, Figure 1 is a diagrammatic plan view of a portion of a plant embodying the apparatus of my invention. 35 Fig. 2 is a vertical sectional view thru my preheater.

In the manufacture of sulfuric acid by one well known method, it is necessary to preheat the sulfuric gases after they have 40 been filtered and purified, to about 750° F. before they enter the converter. This is done by circulating the gases thru a series of U-pipes heated on the outside by hot gases from an oil burner. This involves 45 great waste of fuel as fully 50% of the heat is used to maintain the temperature of the preheater, the radiation and stack losses being very high.

In accordance with my process, I bring 50 the sulfur gases into direct contact with a flame immediately before they enter the converter, thus eliminating all stack losses and the greater portion of radiation losses since the sulfur gases take up nearly all of 55 the flame heat and at once enter the con-

verter. I use a mixture of fuel gas and air in proper proportions to give complete combustion and discharge the fuel mixture under pressure into the path of the sulfur gases. Either illuminating or producer gas 60 is satisfactory for my process, and after adjustment of the quantity of fuel mixture to give the desired temperature to the sulfur gases, little attention is required. If desired, thermally responsive means of well 65 known type may be used to automatically vary the fuel so that a constant temperature is maintained automatically.

In a sulfur burning plant my system of preheating makes the complicated purifying system usually needed, unnecessary, as any sublimed sulfur entrained in the sulfur 70 gases is oxidized by the flame. In this case the gases may be led directly into my preheater from the combustion chamber.

In order to practice my process, the sulfur gas is conducted by pipes 2 into the heaters 3 and from these into the converters 4, thru pipes 6, which are enough smaller than the heaters to baffle the escape of the 75 gases until their temperature has risen to the desired degree. The heater comprises a conduit or section of pipe having an intake preferably on the side, and for convenience may be formed of a T and straight 80 coupled together as shown. Supported on suitable legs 7 in the heater below the inlet is a pipe 8, comprising a hood open at both ends. Thus, gas entering the heater flows around the annular space surrounding the 85 hood and then into the chamber 9 at the end of the hood.

Arranged in the hood on the detachable head 11 is the burner head 12, to which is fed under low pressure a mixture of fuel 90 gas and air in the proper proportions for perfect combustion. The flames from the burner emerge from the hood into the chamber 9 when they come into direct contact with the SO₂ gas, giving up their heat to 95 the gas and oxidizing any sublimed sulfur entrained therein.

The chief function of the hood is to provide protection or shield for the flame. Although a small amount of sulfur gas also 100 flows thru the hood, its volume and velocity are insufficient to affect the flame. To a certain extent the gas flowing around the hood is heated by it, and this is made use of 105 to keep it from becoming overheated as it 110

would otherwise do. The cool gases flowing over the outside prevent the hood from gaining an excessive temperature, and from the inside of the hood the flames and hot products of combustion emerge into the already partially heated sulfur gas. Thus a combustible gas is kept burning in the midst of an incombustible gas, practically all of the heat of combustion being taken up by 10 the incombustible gas. Suitable insulating lagging 13 should surround the heater for highest economy.

I claim:

1. A heater for gases comprising a conduit thru which said gases flow, a hood arranged in the conduit, and means for pro-

jecting a flame from said hood into said conduit.

2. A heater for gases comprising a conduit thru which said gases flow, a tubular 20 hood arranged in the conduit, and a fuel gas burner arranged in the hood.

3. A heater for gases comprising a conduit thru which said gases flow and having the inlet for said gases in the side thereof, 25 a tubular hood arranged in said conduit and extending therein past the inlet aperture, and means for introducing a combustible gas within said hood.

In testimony whereof, I have hereunto set 30 my hand.

ALFRED R. KOLB.
